UNITED STATES PATENT OFFICE

2,000,407

BOTTLE AND CLOSURE THEREFOR

Samuel C. Miller, Louisville, Ky., assignor to
Frankfort Distilleries Incorporated, Louisville,
Ky., a corporation of West Virginia

Application June 29, 1933, Serial No. 678,289

1 Claim. (Cl. 215—44)

The present invention relates to improvements in bottles and closures therefor, and more particularly relates to an improved closure for medicinal or other whiskey packages in which a dose cup is applied to the bottle in a novel manner rendering it possible to remove the cup in a quick manner.

Another object of the invention resides in providing an improved construction of bottle having a dose cup and protected by revenue seal in which the seal will be kept from contact with or destruction from the dose cup.

A further object of the invention is to provide an improved bottle and closure construction in which an effective seal is provided.

With the foregoing and other objects in view, the invention will be more fully described hereinafter, and will be more particularly pointed out in the claim appended hereto.

In the drawing, wherein like symbols refer to like or corresponding parts throughout the several views,

Figure 1 is a fragmentary side elevation of a bottle and closure with the dose cup above the bottle neck.

Figure 2 is a similar view with the dose cup and parts of the closure in section, and

Figure 3 is a vertical section taken on the line 3—3 in Figure 2.

Referring more particularly to the drawing, 5 represents generally a bottle, such as that in which medicinal or other whiskey is dispensed, and 6 indicates the breast of the bottle having the bottle neck 7 with the shouldered part 8, frustoconical section 9 and screw cap 10.

The plain cylindrical portion 7 between the shoulder 8 and conic section 9 is provided with diametrically opposite ribs 11 having their lower surfaces 12 formed substantially spirally. These ribs 11 extend partially around the bottle neck at opposite sides and both ends are spaced apart, as shown in Figures 1 and 2, to provide gaps for receiving the end portions of the revenue stamp represented at 13. This revenue stamp has its intermediate portion enveloping the screw cap 10 and its end portions extended down the sides of the bottle neck and down upon the bottle itself.

A sealing envelope 14 of "Cellophane" or other desired material is placed about the screw cap, revenue stamp and all or a major portion of the neck of the bottle. Such envelope extends below the ribs 11 so as to encompass all portions of such ribs including the under sides 12 thereof and to further provide cylindrical bearing portions 15 below such ribs and lying against the plain cylind-

rical portion 7 of the neck below the ribs. These bearing portions 15 are adapted to slidably receive the lugs 16 upon the dose cup 17.

Two ribs 16 are provided at diametrically opposite points upon the dose cup in order to cooperate with the two ribs 11. The lugs 16 are of a length to fit down through the spaces between the ribs 11. Such lugs 16 are also preferably inclined or spirally formed, as indicated in Figure 1.

The dose cup is preferably, although not necessarily, of the stepped form illustrated and will be of a suitable capacity for the purpose desired.

In operation, after the liquor or other material is placed in the bottle and the cap 10 put in place, 15 the revenue stamp 13 is affixed with its end portions following the contour of the conic section 9, cylindrical portion 7 and shoulder 8 and also the sides of the bottle. The envelope 14 is molded or otherwise placed over the bottle neck so as to 20 enclose the cap 10 and the bottle neck down to and including the cylindrical portion 7. As shown in Figure 3 this envelope 14 will crimp the revenue stamp 13 against the shoulder 8 and hold same securely in position. The revenue stamp 25 will also be forced inwardly against the conic section 19. The inverted dose cup 17 is then placed in the position indicated in Figure 1 and lowered so that the lugs 16 pass downwardly through the spaces between the ribs 11. The 30 cup 17 is then rotated through a partial turn in order to cause the lugs 16 to ride down upon the inclined lower edges 12 of the ribs.

This action will cam the lower edge of the cap 35 against the breast 6 of the bottle forming a tight fit. The dose cup 17 is removed by reverse rotation followed by an axial lifting of the cup upwardly when the lugs 16 align with the spaces between the ribs 11. The envelope 14 may be cut from the bottle neck by passing a knife or other 40 sharp instrument around about the conic section or other part, it being noted that an internal space is formed at the upper stepped portion of such conic section. The glass ribs 11 may be blown in the neck of the bottle. The dose cup 45 engages these ribs without disturbing the stamp 13.

It is obvious that various changes and modifications may be made in the details of construction and design of the above specifically described embodiment of this invention without departing from the spirit thereof, such changes and modifications being restricted only by the scope of the following claim.

What is claimed is:—

A bottle having a neck, a closure for the neck, spaced locking ribs on said neck, a revenue stamp over the top of said closure and extending down between the locking ribs, an envelope covering the neck and extending below said locking ribs adapted to crimp the revenue stamp against the neck and to provide a bearing surface on the

undersides of said ribs, a dose cup provided with lugs corresponding to and adapted to cooperate with said locking ribs through the bearing surface of the envelope, and a shoulder on the bottle at the base of the neck comprising the breast of the bottle and adapted to engage the rim of the cup.

SAMUEL C. MILLER.
